(57) **CLAIM**

The ornamental design for a automobile seat cover for accessories, as shown and described.

DESCRIPTION

FIG. 1 is a top plan view of an automobile seat cover for accessories.

FIG. 2 is a bottom view of the automobile seat cover for accessories.

FIG. 3 is a left side view of the automobile seat protector, the right side view being a mirror image;

FIG. 4 is a top view of the automobile seat cover for accessories; and,

FIG. 5 is a bottom view of the automobile seat cover for accessories.

The cross-hatched shading shown in FIGS. 1 and 2 is understood to cover the surface on which it is applied.
